UNITED STATES PATENT OFFICE.

JOHN B. OHLSON, OF CHICAGO, ILLINOIS, ASSIGNOR TO THE VORTEX MFG. CO., OF CHICAGO, ILLINOIS, A CORPORATION OF ILLINOIS.

DISPENSING CONTAINER.

Application filed September 2, 1924. Serial No. 735,227.

This invention relates to a dispensing container and particularly to a device which is adapted for containing a plurality of nested articles such as paper drinking cups which are to be individually removed therefrom as needed for use.

In devices of this kind it is desirable that the articles in the container be protected from contamination by dust and the like and it is also highly desirable that they be positioned at all times ready for convenient individual removal. Devices for this purpose as heretofore provided have not successfully met these requirements in that the articles were not properly protected or were not maintained towards the position for convenient individual removal.

It is an important object therefore of the present invention to provide a dispensing container which is inexpensive, durable, attractive in appearance and which satisfactorily and effectively meets all the requirements of such devices in commercial use.

It is a further object of this invention to provide a dispensing container wherein the nested articles are at all times submitted to an applied positioning force for retaining the same in proper association with each other for facilitating the convenient individual removal of the articles therefrom.

It is another and important object of this invention to provide a dispensing container of the kind described wherein means automatically movable and not necessarily aided by gravity permit the exteriors of the contained articles to be successively exposed for individual removal.

It is also an important object of this invention to provide a dispensing container which operates effectively with flangless articles to dispense the same individually.

It is finally an important object of this invention to provide an apparatus of the kind described wherein the stack of articles is stationary, wherein the exposé of successive articles for removal is entirely automatic and wherein there is no disfigurement of the articles occasioned by such removal.

Other and further important objects of this invention will be apparent from the disclosures in the specification and the accompanying drawings.

This invention (in a preferred form) is illustrated in the drawings and hereinafter more fully described.

On the drawings:

Figure 1 is a front elevation of a dispensing container for flat nested paper drinking cups embodying the principles of this invention.

Figure 2 is an enlarged vertical section taken on the line 2—2 of Figure 1 with parts shown in elevation.

Figure 3 is an enlarged bottom plan view of the dispenser shown in Figure 1.

Figure 4 is a slightly reduced section on the line 4—4 of Figure 2 with parts omitted.

Figure 5 is an enlarged fragmentary detail section on the line 5—5 of Figure 2.

As shown on the drawings:

The reference numeral 1 indicates the body of the container proper which as will be noted comprises a tubular member or rectangular section open at its lower end and having a longitudinal opening in its front wall communicating with said open lower end. The container is preferably constructed of stamped metal and the upper end thereof is closed with a suitable hinged cover 2 to prevent dust and dirt and other foreign material from contaminating the articles therein. Secured to the inside of the upper end of the container is a fixed flange or retaining means 3 having an opening 4 therein through which articles to be dispensed by the container may be inserted. This opening as will be noted is of approximately oval shape and in the present embodiment is adapted to have inserted therethrough a stack of nested or interfitted flat paper drinking cups which are indicated in Figure 1 by the reference numeral 5.

Secured to the inside of the side walls of the container 1 and extending longitudinally thereof are trough shaped guiding members 6 which are adapted to frictionally engage the edges of the cups 5 and which are provided with transverse indentations 7 which aid in the frictional engagement between the edges of the cups and said guide members 6. As will be noted from an examination of Figures 2 and 3 the ends of said guide members are flared outwardly as indicated by the reference numeral 8 in order to facilitate the insertion and removal of the cups and also to strengthen the construction. The inner longitudinal edges of the front wall of the container along the sides of the opening therein are bent back upon the inner face of the front wall as indicated at 9 to 110

reinforce said edges and secured to the inside of the container adjacent said reinforced edges are channel members 10 which afford guide ways for telescopically arranged plates 11 and 12 which are adapted to be moved downwardly in said guide ways to close said longitudinal opening in the front of the container and to protect the nest of articles inside the container. Secured to the inside of the plate 12 at the lower end thereof is a plate 13 having a flange member 14 extending angularly and downwardly from the lower edge thereof, said flange member being cut out as indicated at 15 to conform to the contour of the outer surface of the nest of cups which it frictionally engages. Extending inwardly from each side of the plate 13 is a member 16 which terminates in an integral trough-shaped portion 17 which slidably engages in the trough-shaped guide member 6. Connected between one edge of the member 14 and a suitable bracket 18 secured to the side wall of the container directly beneath the flange 3 is a helical spring 19 which acts to normally urge the plate 13 and the member attached thereto toward the top of the container and the flange 3.

When the nest of articles is inserted in the container the same is forced through the oval-shaped opening 4 into engagement with the cut out 15 in the member 14, the edges thereof engaging in the trough-shaped member 17, and the insertion of the cups into such engagement is facilitated by bent down guide ears 20 formed at the upper ends of the said members 17. As the nest of cups is pushed into the container through the opening 4, the plate 13 and the plate 12 move downwardly elongating the spring 19 until the bottom edge of the plate 11 is reached at which time ears 21 on the upper edge of said plate 12 engage flange ears 22 on the plate 11 and said plate 11 is then forced downwardly until stopped by the engagement of said ears with notches 23 in the channel members 10.

When the container has thus been filled with articles to be dispensed it will be noted that said articles are held stationary in the container and are also held in association with each other by the tension of the helical spring 19 which tends to draw the plate 13 and the members attached thereto which, of course, frictionally engage the lowermost article toward the flange 3. It is to be noted that the articles when inserted in position in the container, due to the inherent resiliency thereof, spring outwardly to the lower edge of said flange 3 and consequently can only be removed by pulling them individually from the lower end of the container past the cut out portion 15 of the member 14.

It will be readily seen that as the articles

are individually removed from the container the plates 12 and 11 will be successively moved upwardly by the action of the spring 19 to present or expose successive articles for removal in the manner described. This action is illustrated in dotted lines in Figure 1 which indicates the relative position of the lower edge of the plate 12 and the lowermost cup 5 as the cups are successively removed. It will be apparent that this invention provides a dispensing container wherein the cups or other articles nested therein are held stationary relative to the container and wherein the interior of said articles is protected at all times from contamination by dust or other foreign matter. At the same time the telescoping movement of the plates 12 and 11, as the articles are removed from the container by being frictionally drawn past the member 13, provides for the successive exposing of the lowermost article for removal until all of the articles are in fact removed from the container.

The device provided is inexpensive, attractive in appearance and durable and the articles as removed therefrom are not damaged and as will be apparent when withdrawn are properly opened out in position for immediate use.

I am aware that many changes may be made, and numerous details of construction may be varied through a wide range without departing from the principles of this invention; and I therefore do not purpose limiting the patent granted hereon, otherwise than necessitated by the prior art.

I claim as my invention:

1. In a dispenser, means adapted to contain a plurality of articles in association with each other, a slidable support in said means, and a spring for automatically moving said support upwardly in said means to hold said articles stationary and successively expose the same for removal therefrom.

2. In a dispenser, means adapted to contain a plurality of articles in association with each other, slidable wall sections in said means, an article support secured to one of said walls, and mechanisms for actuating said support and walls to successively expose articles for removal from said means.

3. The combination with a container adapted to hold a plurality of nested articles therein, of collapsible means movable relative to the container for retaining said nest of articles in stationary position, and operating means connected with said collapsible means for shortening the length thereof as individual articles are successively removed from the bottom of the container.

4. The combination with a container adapted to have a plurality of nested articles contained therein and stationary relative to said container, a slidable wall in said container, an article supporting means se-

cured to said wall and movable therewith as individual articles are successively removed from the container, and flexible means supporting said article supporting means.

5. 5. In an article dispenser, means for containing a plurality of nested articles, and a spring supported cup holder in said containing means automatically movable for maintaining said nest of articles stationary relative to the container as the same are successively removed therefrom.

6. In an article dispenser, means for containing a plurality of nested articles, a member slidable in said containing means frictionally engaging certain of said articles, slidable closure plates supporting said member, and resilient means for operating said member and plates for maintaining said nest of articles stationary relative to the container as the same are successively removed therefrom.

7. In a device of the class described, a tubular member having a longitudinal opening therein, telescopic means for closing said opening, and slidable means in said tubular member supported on said telescopic means and adapted to carry a plurality of articles and successively expose the same for removal by the movement of said telescopic means.

8. In an article dispensing device of the class described, a tubular article carrying member having a longitudinal opening therein, telescopic means for closing said opening, and means tending to collapse said telescopic means and successively expose articles for removal as said telescopic means are permitted to collapse by the removal of a preceding article.

9. In an article dispensing device of the class described, a tubular member adapted to carry a plurality of articles and having a longitudinal opening and a bottom outlet therein, and telescopic means associated with the opening engaging certain of said articles and movable into engagement with other of said articles as the articles are removed from the tubular member through said bottom outlet.

10. An article dispensing device of the kind described comprising an article carrying container open at one end and having a longitudinal opening communicating with said open end, fixed retaining means at the end of the container opposite said open end, said retaining means adapted to have the end article abut said fixed retaining means, movable retaining means frictionally engaging the article at the end of the nest opposite said fixed retaining means, and means normally urging the movable retaining means toward the fixed retaining means.

11. An article dispenser device of the kind described comprising an article carrying container open at one end and having a longitudinal opening communicating with

said open end, fixed retaining means at the end of the container opposite said open end against which the end article abuts, movable retaining means frictionally engaging the article at the end of the nest opposite said fixed retaining means, means normally urging the movable retaining means toward the fixed retaining means and telescopically arranged, protective means movable with the movable retaining means to close the longitudinal opening over the articles and to telescope as the articles are withdrawn from the end opening.

12. An article dispensing device of the kind described comprising an article carrying container open at one end and having a longitudinal opening at one side thereof, fixed retaining means at the end opposite said open end, said fixed retaining means having an opening therein adapted to have the articles to be dispensed inserted therethrough with the end article abutting the fixed retaining means, and spring actuated movable retaining means frictionally engaging the end article nearest the open end of said container.

13. An article dispensing device of the kind described comprising a container adapted to carry a stack of articles, said container open at one end and having a longitudinal opening in one side thereof, fixed retaining means at the end of the container opposite said open end adapted to be contacted by the end article at one end of said stack of articles, movable retaining means frictionally engaging the article at the other end of the stack of articles, means normally urging the said movable retaining means toward the fixed retaining means and longitudinally guiding means inside the container frictionally engaging the articles therein.

14. A device of the kind described comprising a container adapted to hold a stack of articles, said container open at one end and having a longitudinal opening in one side thereof, fixed retaining means at the end of the container opposite said open end and contacted by one end of said stack of articles, a removable cover for the end of the container adjacent said fixed retaining means, and movable retaining means frictionally engaging the other end of the stack of articles and normally urging the movable means toward the fixed retaining means.

15. The combination with a container adapted to hold a nest of interfitting articles stationary therein and individually removable therefrom, of a positioning follower automatically movable upwardly into frictional engagement with the end-most article of the stationary nest of articles as the articles are successively removed from the container.

16. The combination with a container adapted to carry a nest of interfitting arti-

cles stationary therein and individually removable therefrom, of a spring actuated follower held in frictional engagement with the endmost article of the nest.

17. The combination with a container adapted to carry a nest of interfitting articles stationary therein and individually removable from the lower end thereof, of a movable article positioning follower automatically maintained in engagement with the lowermost article as the articles are successively removed from the container.

18. The combination with a container adapted to carry a nest of interfitting articles stationary therein and individually removable from the lower end thereof, of a movable article positioning follower automatically maintained in engagement with the lowermost article as the articles are successively removed from the container, and telescopic article protecting means operatively connected with said follower.

19. The combination with a container

adapted to hold a stack of articles therein, of fixed retaining means therein, and movable retaining means in the container normally tending to move toward the fixed retaining means for holding the stack of articles stationary as the articles are individually removed from the container at a point adjacent said movable retaining means.

20. The combination with a container adapted to hold a stack of articles therein, of fixed apertured retaining means in said container, a movable retaining means mounted in the container, and a spring connected to said movable retaining means, said articles being positioned between said retaining means and adapted to be successively frictionally engaged with said movable retaining means and individually movable therepast.

In testimony whereof I have hereunto subscribed my name.

JOHN B. OHLSON.
